UNITED STATES PATENT OFFICE.

RALPH A. WILLISON, OF PORTLAND, OREGON.

FLASHING FOR SIDEWALK-LIGHTS.

1,243,235.

Specification of Letters Patent. Patented Oct. 16, 1917.

Application filed September 7, 1916. Serial No. 118,846.

To all whom it may concern:

Be it known that I, RALPH A. WILLISON, a citizen of the United States, residing at Portland, in the county of Multnomah and State of Oregon, have invented certain new and useful Improvements in Flashings for Sidewalk-Lights; and I do declare the following to be a full, clear, and exact description of the invention, such as will enable others skilled in the art to which it appertains to make and use the same.

My invention aims to provide simple and efficient means for preventing leakage around vault lights and the like placed in sidewalks, and to this end, the invention resides in certain novel features of construction and in unique combinations of parts to be hereinafter fully described and claimed, the descriptive matter being supplemented by the accompanying drawings which constitute a part of this application and in which:

Figure 1 is a plan view of a portion of a sidewalk and a skylight therein showing the application of the invention;

Fig. 2 is a vertical section on the plane of the line 2—2 of Fig. 1;

Figs. 3 and 4 are perspective views of portions of the inner and outer frames employed in constructing the leak-proof joint; and

Fig. 5 is likewise a perspective view showing a different form of construction.

In the drawings, the numeral 1 designates a rough foundation of a sidewalk and 2 the finishing layer of cement or concrete which constitutes the walk proper, this walk having a rectangular opening 3 to receive therein a light-carrying slab.

An outer rectangular frame 4 is disposed in the opening 3, the side and end bars of said frame being L-shaped in cross section with their horizontal base flanges 5 embedded in the wall of the opening 3 and with their vertical webs or flanges 6 spaced inwardly from said wall and terminating below the surface of the walk. The outer edges of the flanges 5 are provided with longitudinally extending vertically disposed flanges 7 preferably formed by bending said edges first upwardly and then downwardly.

An inner frame 8 is disposed within the frame 4 and the side and end bars of said frame 8 are likewise L-shaped in cross section, the horizontal base flanges 9 of these bars having vertical flanges 10 on their free edges as is the case with the flanges 5. The vertical flanges 11 of the frame 8 contact with the flanges 6 and are bent outwardly and downwardly to form seats receiving said flanges 6 therein as depicted clearly in Figs. 2 and 3. The horizontal flanges 9 are embedded in the edges of a slab 12 which is constructed of cement, concrete or the like, said edges being spaced from the vertical flanges 6 as shown. The slab 12 is supported by a frame 13 of the usual or any preferred construction and carries the lights 14.

Although this feature is not absolutely essential, the base flanges of both frames 4 and 8 are preferably perforated in longitudinal rows in order that they may be more effectively anchored within the cement or other material of which the walk and slab are constructed.

A filler 15 of any suitable water-tight plastic material is employed to fill the space between the wall of the opening 3 and the edge of the slab 12, said filler covering the vertical flanges of both frames as shown and terminating flush with the surface of the walk and slab.

In constructing the improved joint, the base 1 of the sidewalk is first laid, leaving the rectangular opening therein and this having been done, the layer 2 is applied, the outer frame 4 being held in proper position while this is being done, by any preferred means. To prevent the material of which layer 2 is constructed from coming into contact with the vertical web 6 of the frame 4, a thin strip of wood is placed against the outer surface of said web and is removed when the material in question is set. The frame 13 is next placed within the opening 3 and held in proper position by an appropriate scaffold or the like and the lights 14 are placed on said frame. The frame 8 is now hooked on the frame 4 after which the plastic material of which the slab 12 is constructed, is applied around the upstanding lights and above and below the

horizontal flanges 9. During this operation, a thin wooden strip will be placed between the vertical flanges 11 and the material of which the slab is constructed. When 5 this material is set, the strip in question will be removed thus leaving sufficient space for the filler 15, which filler is now applied.

All joints of the two frames will be well soldered or otherwise secured before the 10 plastic material is applied around said frames and when this material has hardened, it will be obvious that an extremely effective water-tight connection will prevail.

In Fig. 5, a modified form of construction is shown in which is illustrated a fragment of an inner and outer frame constructed of one piece of metal stamped into inverted T-shape in transverse section. In this form of the invention, the two plies of 20 the vertical web 20 are spaced apart near their lower edges to permit expansion and contraction of the joint when completed and the horizontal base flanges 21 extend outwardly in opposite directions from the 25 lower edges of said plies, the outer edges of said flanges being bent first upwardly and then downwardly to provide longitudinal flanges 22 similar in all respects to the flanges 7 and 10. In this type of invention 30 as well as that previously described, the base flanges are preferably perforated.

The joint just described may well be used wherever a water-tight construction is required, yet one which will permit expansion 35 and contraction. For instance, it may be employed to advantage in the construction of reservoirs.

In the foregoing, I have described a number of specific details of construction for the 40 attainment of probably the best results and in the drawings, these details have been illustrated, but it is to be understood that within the scope of the invention as claimed, numerous changes may be made without 45 sacrificing the principal objects.

I claim as my invention:—

1. The combination with a sidewalk having an opening to receive a light-carrying slab; of a frame whose sides and ends are 50 of inverted T-shape in cross section, said frame being disposed in the opening with approximately the outer half of its horizontal base embedded in the walk and with its 55 vertical web spaced inwardly from the wall of said opening and terminating below the surface of the walk, a light-carrying slab within the aforesaid frame and having its inner edge spaced from said vertical web, the inner half of said base being embedded 60 in said edge of the slab, and a water-tight filler covering the aforesaid web and filling the space between the slab and walk.

2. The combination with a sidewalk hav-

ing an opening to receive a light-carrying slab; of a frame whose sides and ends are 65 of L-shape in cross section, said frame being disposed in said opening with its horizontal flange extending outwardly and embedded in the wall thereof, the vertical flange of said frame being spaced from said wall 70 and terminating below the surface of the walk, a second frame within the other and also having L-shaped side and end bars whose horizontal flanges extend inwardly and whose vertical flanges are directed outwardly and downwardly over the vertical flanges of the first-named frame, a light-carrying slab in said opening and having its edge spaced from said vertical flanges of the second frame, the horizontal flanges 80 of the latter being embedded in the edge of said slab, and a water-tight filler in the space between the slab and walk and covering the aforesaid vertical flanges.

3. A frame of the class described consisting of an outer frame whose side and end bars are L-shaped in cross section with their horizontal flanges extending outwardly, and an inner frame within said outer frame, the side and end bars of said inner frame being 90 also L-shaped in cross section with their horizontal flanges extending inwardly and with their vertical flanges directed outwardly and downwardly around the vertical flanges of said outer frame.

4. A frame of the class described consisting of an outer frame whose side and end bars are L-shaped in cross section with their horizontal flanges extending outwardly, and an inner frame within said outer frame, the side and end bars of said inner frame being 100 also L-shaped in cross section with their horizontal flanges extending inwardly and with their vertical flanges directed outwardly and downwardly around the vertical flanges of said outer frame, the free edges of the horizontal flanges of both frames being bent upwardly and then downwardly to form longitudinally extending vertically disposed anchoring flanges.

5. A reinforcing device for the meeting edges of a pair of molded slabs, said device being in the form of an elongated bar-like structure formed of malleable sheet metal bent into the form of a T in transverse section, the outer edges of the oppositely extending flanges of the T being bent first in one direction and then in the other to provide longitudinal anchoring flanges.

6. A reinforcing device for the meeting edges of molded slabs comprising a metal bar L-shaped in transverse section and adapted to have its horizontal flange embedded in one slab, a second metal bar L-shaped in transverse section adapted to have its horizontal flange embedded in the other slab,

the vertical flanges of the two bars being in contact and the upper edge of one of these flanges being bent outwardly and downwardly to form a hook receiving the upper 5 edge of the other flange.

In testimony whereof I have hereunto set

my hand in the presence of two subscribing witnesses.

RALPH A. WILLISON.
